CLAIM

The ornamental design for a pair of novelty spectacles,
as shown and described.

DESCRIPTION

FIG. 1 is a perspective view of a pair of spectacles
showing my new design;

FIG. 2 is a front view thereof;

FIG. 3 is a right side elevational view thereof, the side
opposite being a mirror image; and,

FIG. 4 is a top view thereof.

Fig. 1Fig. 2Fig. 3Fig 4.
